UNITED STATES PATENT OFFICE

WILLIAM EDWARD RUPP, OF HILLSBORO, KANSAS

MOP WRINGER AND PAIL SUPPORT

Application filed November 23, 1931. Serial No. 576,878.

This invention relates to improvements in mop wringers and pail supports and pertains to a construction which is adapted to support a pail below rollers on a frame that is movable around to meet the convenience of the operator.

The primary object of the present invention is a novel construction for moving one of the rollers to a compressing position by the foot of the operator.

Further objects of the invention will appear from the following description:

Figure 1 is a side elevation of an improved mop wringer and pail supporting device which embodies my present improvements.

Figure 2 is a top plan view of Figure 1.

Figure 3 is a detached view showing the construction of the vertically movable holder for the said pail.

In carrying out the present improvement, I provide a supporting frame 1 for a pail, the said supporting frame being provided with upwardly projecting members which will now be described.

25 Supporting frame

Attention is directed to the special construction of the supporting frame 1, in that it comprises two parallel portions which are connected with each other by suitable connecting rods 2. The front end of the frame 1 is curved upwardly and forwardly as shown at 3, and attached to the front end of this curved portion is a suitable caster arrangement 4 that carries relatively large wheels 5 that are provided with rubber tires 6. The rear end is constructed similar to the front end in that it has the rearwardly curved portion 7 that carries a caster 8 and has a rubber tire wheel 9 attached to it. As stated, the frame comprises two parallel portions 1 and each parallel portion is provided with the upwardly curved members 3 and 7.

At each side a member 10 has its front end riveted to the forwardly curved portion 3 and this member 10 extends rearwardly and upwardly and is riveted as shown at 12 to the upper portion of standards 13 that have their lower ends 14 riveted to the horizontal portion 1 of the supporting frame. There are,

of course, two upwardly extending members 13 and two rearwardly and upwardly extending members 10.

Journalized in the upper ends of the members 13 is a suitable roller 15 and supported below this roller is a trough-like member 16 that is inclined from its rear to its front edge whereby the water from this roller is caught in this trough-like member 16 and flows over its inner edge into the bucket or pail.

A second movable roller 17 is journalized in the upper free ends of the members 18, the said members being bent at an inclination intermediate their ends at substantially point 19. The rear ends 20 of the members 18 are pivotedly connected at 21 with foot operated members 22 which have their forward ends pivotedly connected at 23 with the rearwardly and upwardly extending members 10 and preferably just above their lower ends. These members 22 have their ends connected by a foot portion 24, which, in the form here shown, is made continuous with the members 22 and 24. Of course this construction might be varied and the part 24 made separate and having its ends rigidly connected with the rear ends of the members 22, which in effect will make the same construction and operation as that here shown.

For the purpose of forming a suitable bearing for rollers 25, which are carried by the members 10, the said members have their upper ends doubled inward and journals 26 for the roller have their ends passing through the parallel portions 27 and 29 of the members 10.

The members 18 pass through the openings 29 formed by the doubling inward of the member 10 and the undersides of the bent portions 30 of the members 18 engage the said rollers as shown. A suitable spring or springs 31 have their upper ends connected to the extremities of the members 10 and their lower ends connected with the members 22 whereby the springs normally hold the roller 17 and the member 18 in the positions shown in solid lines, Figure 1.

When, however, it is desired to compress a mop, not shown, then the operator presses the member 24 with his foot, thus lowering

the members 22, causing the underside 30 to engage with the rollers 25, whereby the roller 17 is brought into position to compress the mop (not shown) between the rollers 17 and 15.

For the purpose of holding the pail in its position on the frame, a vertically movable latch 32 is connected with a band 33 that has its inner ends 34 riveted to the members 13 and the band is bent around the said pail. This latch 32 has a slot 35 in which a pin 38 passes whereby the latch may be moved vertically for releasing the pail and when it drops, its upper hooked end 36 embraces the upper edge of the said pail.

This device can be readily moved around from place to place while it is being used by reason of the casters 4 and 8 and the mop compressed by depressing the member 24, thereby carrying the roller 17 against or adjacent the roller 15 with the mop between the rollers.

It will be observed from the foregoing that the part 1 is in effect a support for a frame consisting of the members 10 and 13 to which a roller 15 is journaled, thus constituting a rigid support for the said roller 15. From the foregoing description it will also be understood that the members 22 and the members 18 which carry a roller, are movable, and that the members 18 have a combined swinging and cam action that throws the roller 17 adjacent the roller 15.

Having thus described my invention, what I claim and desire to secure by Letters Patent is:

1. A combined pail support and wringer comprising a base adapted to receive a pail, front and rear members having their lower ends rigidly connected with said base and their upper ends also rigidly connected together, a horizontal roller extending across the said base and supported by the upper end of one of said members, a depressible foot member having its forward end pivotally connected with the said front member, the said front member having portions on each side of the base, each of said portions intermediate its ends having a bearing support, a swinging member having parts located at opposite sides of the base and supporting at its upper end a roller, said swinging members extending downwardly and rearwardly and pivotally connected with a foot member, a roller carrying member being laterally bent upwardly at a point beyond its lower end, a spring for normally holding the foot member upward, whereby a depression of the foot member causes the swinging roller member to travel adjacent the horizontal roller for the purpose described.

2. A combined pail support and wringer comprising a frame adapted to detachably receive a pail, members having their lower ends rigidly connected with the said frame

and projecting upward and supporting a horizontal roller between their upper ends, members having their upper ends rigidly connected to the upper ends of the members, the upper ends of the members made in two overlapping parts supported in separated relation, rollers journaled between the overlapping parts, a foot depressible member pivotally connected at its forward end with the member, swinging members pivotally connected at their rear ends with the said depressible member, said swinging members passing through between the separated portions of the members and resting on the said roller, said swinging members supporting between their upper ends a roller, means for holding the said foot depressible members normally in an upward position, whereby the said parts operate as specified.

In testimony whereof I hereunto affix my signature.

WILLIAM EDWARD RUPP.
